UNITED STATES PATENT OFFICE.

OSCAR W. SMITH, OF DETROIT, MICHIGAN.

DESIGN FOR A PAPER-CLIP.

SPECIFICATION forming part of Design No. 24,073, dated February 26, 1895.

Application filed December 8, 1894. Serial No. 531,287. Term of patent 14 years.

To all whom it may concern:

Be it known that I, OSCAR W. SMITH, a citizen of the United States, residing at Detroit, county of Wayne, State of Michigan, have invented a certain new and useful Design for a Paper-Clip; and I declare the following to be a full, clear, and exact description of the invention, such as will enable others skilled in the art to which it pertains to make and use the same, reference being had to the accompanying drawings, which form a part of this specification.

Figure 1 is a front view. Fig. 2 is a rear view, and Fig. 3 is a longitudinal section. The leading feature of the design is found in the oval shaped back provided with an oval shaped perforation, across which lies the long narrow jaw that forms the front of the clip.

A indicates the back, which is in the form of an oval ring, from the pointed end of which extends the connection B, which, bending in a rather sharp or small half circle at C, is narrowed into a long narrow jaw D, which lies across the oval hole a and extends over the edge of the ring A and terminates with the round ended projection E.

What I claim is—

The design for a paper clip substantially as shown and described.

In testimony whereof I sign this specification in the presence of two witnesses.

OSCAR W. SMITH.
